US00D478888S

(12) **United States Design Patent**
Ng

(10) Patent No.: **US D478,888 S**
(45) Date of Patent: **** Aug. 26, 2003**

(54) **MP-3 DIGITAL AUDIO PLAYER WITH
BATTERY PACK**

D340,300 S * 10/1993 Yuen D14/168
D344,358 S * 2/1994 Yuen D14/168
D426,223 S * 6/2000 Nomura D14/167
D453,752 S * 2/2002 Lee D14/192
D463,393 S * 9/2002 Kataoka D14/167

(75) Inventor: **Zachary Ng, Hong Kong (CN)**

(73) Assignee: **Koninklijke Philips Electronics N.V.,**
Eindhoven (NL)

(**) Term: **14 Years**

* cited by examiner

(21) Appl. No.: **29/170,082**

Primary Examiner—Nanda Bondade

(22) Filed: **Oct. 31, 2002**

(74) Attorney, Agent, or Firm—Ernestine C. Bartlett

(51) LOC (7) Cl. **14-01**

(57) **CLAIM**

(52) U.S. Cl. **D14/156**

The ornamental design for a MP-3 digital audio player with
a battery pack, as shown.

(58) **Field of Search** D14/135-136,
D14/156-157, 167-168, 188, 193-198,
257-258; 369/75.1, 75.2, 77.1, 77.2; 455/344,
347, 350-351

DESCRIPTION

(56) **References Cited**

FIG. 1 is a perspective view showing my design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof.
